Robert L. Epstein

(57) **CLAIM**

The ornamental design for a gumball float, as shown and described.

DESCRIPTION

FIG. 1 is a perspective view showing the front, top and right side of the first preferred embodiment of my design; FIG. 2 is an elevation view of the front of the first preferred embodiment my design;

FIG. 3 is an elevation view of the rear of the first preferred embodiment my design;

FIG. 4 is an elevation view of the left side of the first preferred embodiment my design;

FIG. 5 is an elevation view of the right side of the first preferred embodiment other side of my design;

FIG. 6 is a top plan view of the first preferred embodiment my design;

FIG. 7 is a bottom plan view of the first preferred embodiment my design;

FIG. 8 is a perspective view showing the front, top and left side of the second preferred embodiment of my design;

FIG. 9 is an elevation view of the front of the second preferred embodiment my design;

FIG. 10 is an elevation view of the rear of the second preferred embodiment my design;

FIG. 11 is an elevation view of the left side of the second preferred embodiment my design;

FIG. 12 is an elevation view of the right side of the second preferred embodiment other side of my design;

FIG. 13 is a top plan view of the second preferred embodiment my design; and,

FIG. 14 is a bottom plan view of the second preferred embodiment my design.
